UNITED STATES PATENT OFFICE.

ELIHU LIPPITT, OF CHICAGO, ILLINOIS, ASSIGNOR OF ONE-HALF TO
GEORGE D. WHITCOMB CO., OF CHICAGO, ILLINOIS, A CORPORA-
TION OF ILLINOIS.

FRAME FOR INCANDESCENT MANTLES.

SPECIFICATION forming part of Letters Patent No. 746,639, dated December 8, 1903.

Application filed March 2, 1903. Serial No. 145,759. (No model.)

To all whom it may concern:

Be it known that I, ELIHU LIPPITT, a citizen of the United States, and a resident of Chicago, county of Cook, and State of Illinois, have invented certain new and useful Improvements in Frames for Incandescent Mantles, of which the following is a specification, and which are illustrated in the accompanying drawings, forming a part thereof.

10 This invention has reference to improvements in the frames or forms used for making incandescent-lighting mantles for gas and other illuminating apparatus; and it consists of a fabricated mantle-frame having a circumferentially-arranged draw-string of incombustible material incorporated into the frame in its fabrication and the ends of which are carried across the open end of the frame and secured to its opposite side, so as to form 20 a bail.

More specifically, it consists of such a frame having a circumferential pocket within which such draw-string is housed and of a plurality of frames fabricated together as a continuous 25 tube with the draw-strings inserted at proper places, so that when the several frames are separated such strings will be at the ends thereof.

30 Preferably the mantle-frames are made in a continuously-connected or integral series and provided at equidistant points, depending upon the intended length of the completed mantle, with integral pockets containing the bail-cords, and then cut up into units as desired. When so severed, the end of each 35 unit in which the supporting-bail is located is gathered in to fashion the upper end of the frame to the shape of the completed mantle, and the loose ends of the cord are twisted, 40 carried over to the opposite side of the frame, and there secured by means of a needle or other suitable implement.

The invention is more fully set forth in the following description, and particularly designated in the appended claims.

45 Referring to the drawings, Figure 1 illustrates a plurality of the frames made in accordance with my invention and before being cut up into units, the lower end of the figure

being in section to show the cord of one of the frames. Fig. 2 shows a completed mantle-frame shaped up into conventional form. Fig. 3 relates to a detail, on an enlarged scale, of the bail-cord and the integral pocket for retaining the same. Fig. 4 is an enlarged 55 section on the line $\alpha\alpha$ of Fig. 3, and Fig. 5 illustrates a modification.

Under the usual practice in attaching the bails to the frames before treatment with oxides for producing the incandescent elements 60 the stocking or tube of combustible fabric is cut into suitable lengths and the bail then attached by folding over one end of the frame or forming a hem in which the bail-cord is placed, or by threading the ends of the cord 65 into the wall of the frame, or in some instances by knotting one end of a cord and passing the other end through the contracted upper end of the mantle, so that the mantle is supported by the knot. The present invention does away with such methods of attaching the supporting-bails as a second or subsequent operation—that is, after the completion of the frame, inasmuch as in its practice the bails are secured to the frames or 75 forms during the fabricating of the latter.

The fabric from which the bodies, as 10, of the frames are made may be knitted or woven into a continuous length or integral series of frames. I have shown the frames in the drawings as being knitted; but it is to be understood that the invention is not limited in this particular and may be made in any other suitable manner, as by a weaving process. At equidistant points, the spacing depending on the 80 intended lengths of the completed incandescent elements, a pocket 11 is knitted around the wall or peripherally of the tube. Such pocket when the fabric is knitted projects beyond and forms a kind of ridge around the 85 tube, but after being cut into units assumes the position shown in Fig. 4. In knitting the pocket 11, which is accomplished by a manipulation of the needles, as will be understood by those skilled in the art to which the invention 90 relates, the web is brought around or back upon itself; but before the pocket is closed, as shown in Fig. 4, a strip of incombustible

cord, as asbestos, of a length a little greater than the perimeter of the tube, as will be seen on reference to Fig. 3, is placed or laid in the pocket, its ends being brought close together, 5 and the pocket is then closed by a continuation of the knitting operation. Before treatment with the material or oxids necessary to produce the incandescent mantle the tube is cut up into individual frames close to the 10 pocket, preferably leaving the selvage edge adjacent thereto. This will leave but one free end of thread or yarn 13, which, being at the selvage edge, cannot pull out or unravel the pocket.

15 In Fig. 5 is illustrated a means for facilitating the separation of the unit-frames, consisting of an independent thread or strand 15, knitted into and connecting the adjacent ends of successive frames. This independent 20 thread is incorporated in the stocking during the fabrication thereof and along the line where the cut would be made in the tube. (Illustrated in Fig. 1.) By pulling upon one 25 end of the thread, so as to withdraw it, the separation of the two frames may readily be effected, the fabric being so made that a selvage edge is left at the pocket. The end of the frame at which the bail is located may then be gathered in, as shown in Fig. 2, the 30 free ends of the cord being afterward twisted, as at 14, carried over to the opposite side of the frame, and there secured by a needle or other suitable implement, or the end may be left straight, if it be desired.

35 After having been given the required shape the mantle is treated in the usual manner and the fabric-frame burned away, leaving an incandescent shell or mantle having an incombustible bail securely attached thereto.

40 I do not claim, broadly, a mantle-body having its bail fabricated into it, as such a structure was first invented by William C. Whitcomb and myself and made the subject of an application for Letters Patent filed December 23, 1902, Serial No. 136,378.

45 I claim as my invention—

1. A frame for an incandescent mantle consisting of a tubular body of combustible material having an integral pocket, and an incombustible cord located in the pocket.

50 2. A frame for an incandescent mantle consisting of a tubular body of combustible material having a peripheral integral pocket, and an incombustible cord located in the pocket.

55 3. A frame for an incandescent mantle consisting of a tubular body of combustible ma-

terial having a peripheral integral pocket, and an incombustible cord in the pocket and the ends of which protrude from the same. 60

4. A frame for an incandescent mantle consisting of a tubular body of combustible material provided with a pocket extending entirely around the wall of the same, and an incombustible cord located in the pocket and 65 having its ends brought close together and protruding from the pocket.

5. A frame for an incandescent mantle consisting of a tubular body of combustible material having an integral closed peripheral 70 pocket at one end, and a cord of incombustible material located in the pocket.

6. A frame for an incandescent mantle consisting of a tubular body of combustible material having an integral closed peripheral 75 pocket at one end, a bail-cord of incombustible material located in the pocket and the said end being gathered in and the ends of the cord extended across the end of the body and secured to the opposite side thereof. 80

7. A frame for an incandescent mantle consisting of a knitted tubular body of combustible material having an integral closed pocket, and a cord of incombustible material located 85 in the pocket.

8. A frame for an incandescent mantle consisting of a knitted tubular body of combustible material having an integral closed pocket at one end thereof and an incombustible cord located in the pocket, and having its ends brought together, and extended across the end 90 of the frame and secured to the opposite side of the same.

9. A continuously-connected or integral series of frames for incandescent mantles, provided with equidistant integral closed pockets, and a bail-cord of incombustible material located in each pocket. 95

10. A continuously-connected or integral series of knitted frames for incandescent mantles provided with equidistant integral peripheral pockets, and a bail-cord of incombustible material located in each pocket and the ends of which are located close together and protrude from the pocket. 100

11. A frame for an incandescent mantle consisting of a fabricated tubular body, and a draw-cord of incombustible material arranged circumferentially thereof and incorporated into the body in the fabrication thereof. 105

ELIHU LIPPITT.
